UNITED STATES PATENT OFFICE.

CHARLES F. J. CHARLISS, OF HOUSTON, TEXAS.

BOLT.

Application filed February 26, 1920. Serial No. 361,435.

To all whom it may concern:

Be it known that I, CHARLES F. J. CHARLISS, citizen of the United States, residing at Houston, in the county of Harris and 5 State of Texas, have invented certain new and useful Improvements in a Bolt, of which the following is a specification.

This invention relates to new and useful improvements in a bolt specially designed 10 to hold two or more plates or other members together, without threads or nuts.

One object of the invention is to provide 15 a bolt which can be inserted and tightened quickly with a stroke of a hammer instead of by the tedious process of screwing on a nut with one wrench, while holding the head with another wrench; and which may be quickly loosened and withdrawn without the reverse process of unscrewing the nut, 20 which is often difficult to remove.

Another object of the invention is to provide 25 a bolt which will not turn when being tightened and therefore which does not require a square or hexagonal head or square shank, thus conduced to economy of material.

Another object of the invention is to provide 30 a bolt which will not become loose as a result of vibration, that is, which may be locked permanently tight without the use 35 of a lock-nut, castle-nut or lock-washer; for this reason and for the further reason that it is quickly applied this form of bolt is particularly useful in bolting on the angle bars or fish plates in the construction of rail- 40 way tracks.

A further feature of the invention is to provide 45 a bolt which is slightly pointed and which has no threads so that it may be driven into holes which are not in exact alignment and will thus draw the plates or members into proper position without injury to the bolt.

With the above and other objects in view, 50 the invention has particular relation to certain novel features of construction, arrangement of parts and use, examples of which are given in this specification and illustrated in the accompanying drawings wherein:

Figure 1 shows an end view of the bolt, 55 showing the wedge shaped key fully seated therein.

Figure 2 shows a side elevation thereof,

Figures 3 and 4 show end and side views, 55 respectively, thereof, showing the key driven in place, said Figures 3 and 4 differing

from Figures 1 and 2 in the respect only that thicker parts are shown connected in the latter than in the former.

Referring now more particularly to the 60 drawings wherein like numerals of reference designate similar parts in each of the figures, the numeral 1 refers to a bolt having the head 2 at one end. The end of the bolt opposite the head has a transverse slot 65 3 cut therethrough. The outer end of this slot, as shown in Figures 2 and 4 is inclined relative to the axis of the bolt, so that the wedge shaped key 4 will wedge tightly in the slot when driven therein; and 70 for convenience in manufacture the inner end of the slot may be parallel with the outer end as is also illustrated in Figures 2 and 4.

As illustrated in Figure 2, two relatively 75 thin plates 5 and 6 are secured together by the bolt. This is accomplished by passing the bolt through aligned bolt holes in said members and then driving the wedge shaped key 4 through the slot 3. As illus- 80 trated in Figure 4 the plates 5 and 6, secured together, are somewhat thicker than those illustrated in Figure 2 and consequently the key 4 can not be driven through as far as shown in Figure 2. The key 4 is 85 formed of any suitable material bent in the U-shaped form with sides pressed closely together. One of the arms of the key is slightly longer than the other both to permit of ready bending with a hammer for 90 locking the wedge in place and also to facilitate entrance of the wedge into the slot and when the key is driven in place, the extended end is bent out at an angle as illustrated in Figures 1 and 3, so as to prevent 95 the key from slipping and thus loosen the bolt. The lower corner of the longer arm is cut away, or beveled upwardly, as at 7, to facilitate the entrance of the key, where the members to be secured together tend to 100 spring apart so that the exposed part of the slot is sufficient to receive the key.

What I claim is:

1. A bolt having its slotted end pointed to facilitate its passage through holes in adjacent members not in perfect alignment, and provided with a slot, and a key bent in U-shaped form, adapted to be fitted through the slot and one arm of which is thinner than the other. 105

2. A securing key formed of a single piece of metal, bent in a U-shaped form, 110

and whose arms lie closely together, one of said arms being longer and thinner than the other, and having its free end beveled in one direction, and the free end of the shorter arm being beveled inwardly.

3. A tapering key of substantially uniform thickness and formed of a single piece of metal bent in a U-shaped form and whose arms lie closely together, one of said arms being longer and thinner than the

other and having its free end beveled in one direction, and the free end of the short arm being beveled inwardly.

In testimony whereof I have signed my name to this specification in the presence of 15 two subscribing witnesses.

CHARLES F. J. CHARLISS.
